[57] CLAIM

Thr ornamental design for a club face pattern on a wood-type golf club head, as shown and described.

DESCRIPTION

FIG. 1 is a front elevational view of a club face pattern on a wood-type golf club head.

FIG. 2 is a top perspective view thereof; and,

FIG. 3 is a bottom perspective view thereof.

The broken lines showing a golf club head are for illustrative purposes only and form no part of the claimed design.
